UNITED STATES PATENT OFFICE.

JAMES ASHFORD AND HERBERT EDWARD NEWEY, OF BIRMINGHAM,
ENGLAND.

PHOTOGRAPHIC-PLATE HOLDER.

SPECIFICATION forming part of Letters Patent No. 689,271, dated December 17, 1901.

Application filed July 8, 1901. Serial No. 67,505. (No model.)

To all whom it may concern:

Be it known that we, JAMES ASHFORD, a resident of 179 Aston road, and HERBERT EDWARD NEWEY, a resident of 54 Victoria street, in the city of Birmingham, England, subjects of the King of Great Britain, have invented new and useful Improvements in Photographic-Plate Holders, (for which we have made application for Letters Patent in Great Britain under No. 1,109, bearing date January 17, 1901,) of which the following is a specification.

Our invention relates to improvements in photographic-plate holders; and the objects of our improvements are an improved envelop in which are incased the films or plates, a double-sided film or plate carrier; also, improved means in the holder for protecting the plates or films from light. We attain these objects by the mechanism illustrated in the accompanying drawings, in which—

Figure 1 is a front view of the plate or film carrier and envelop, part of the envelop being removed to show more clearly the carrier. Fig. 2 is a vertical sectional view of the carrier on line A B, Fig. 1. Fig. 3 is a vertical sectional view on line C D, Fig. 1, showing also the envelop in position. Fig. 4 is a front view of the holder in which is mounted the plate-carrier. Fig. 5 is a side view of the holder, showing it partly open. Fig. 6 is a sectional plan view of the holder when closed on line E F, Fig. 4, without the plate-carrier. Fig. 7 is a vertical sectional view on line G H, Fig. 4, of the holder having the plate-carrier and envelop inclosed.

Similar characters refer to similar parts throughout the several views.

10 is the carrier to receive the plates, films, or other sensitive surfaces, and inasmuch as either the one or the other may be used we shall refer to sensitive surfaces only. On each side of the carrier are flaps 11 11, consisting of an all-round narrow edge, thus leaving the center open for sight. Between the carrier and the flaps are placed the sensitive surfaces for exposure. The upper end of the carrier is enlarged and provided with a continuous recess 12, whose surface is covered with velvet or other similar material 12'.

13 is an envelop made of leather, paper, or

other suitable material, having its one end 14 closed and made light-tight, except its open end 15. This envelop is made to receive the carrier 10, with its flaps and the sensitive surfaces, its open end passing into the recess 12, so that when thus placed the sensitive surfaces are perfectly protected from light. 55

16 is the holder, having the usual exposure-opening at its front and having the hinged door 17.

18 is a spring-pressed follower projecting from the door 17 by the springs 19, so that it may yield to pressure as required.

The interior of the holder is made to receive 65 the complete carrier 10, with its envelop 13, the recess 20 being made to accommodate the enlargement at 20^a on the one side, while the other side of the said enlargement 20^a falls behind the end of the follower 18, as shown 70 in Fig. 7. It will be seen that the envelop may now be withdrawn, and in so doing the carrier 10, with the sensitive surfaces, is retained in the holder. The front marginal surface of the follower 18 and the inside 75 marginal surface around the exposure-opening of the holder are covered with velvet or other similar material 21' 22' to exclude light. The inner face of the holder and outer face 80 of the follower near their upper ends are recessed, as at 21 22, so that the light-excluding surfaces at their upper ends are set back somewhat to a depth a little more than the thickness of the sides of the envelop 13. Consequently as the said envelop is being withdrawn for exposure ere it quite leaves the holder it passes into the recessed portions 21 85 and 22, which are pressed against it by the springs 19, so as to exclude the light past such recessed portions 21 and 22; but as this takes 90 place the front marginal surface of the follower 18 at 23 and the inside marginal surface at 24 have both closed firmly onto the flaps 11 11, so that the light is perfectly shut off thereat ere the possibility takes place of 95 light entering at the opening.

It will be readily understood that having used the one exposure the envelop is simply pushed back again over the carrier and sensitive surfaces, when the door may be opened 100 and the envelop and carrier turned over, the door again closed, and the other sensitive

surface exposed. It will also be clear that our improved envelop may be used for single or double sided film-carriers.

Having thus described our invention, what 5 we claim, and desire to secure by Letters Patent, is—

1. The combination of a carrier having an enlarged head provided with a recess and adapted to carry the sensitive surfaces, and 10 an envelop surrounding said carrier and adapted to have one end thereof engage in said recess.
2. The combination of a carrier having an enlarged head provided with a continuous recess and adapted to carry the sensitive surfaces, and an envelop surrounding said carrier and provided with a closed and an open end, said open end adapted to engage in said recess. 15
3. The combination of a carrier provided with flaps and having an enlarged head provided with a continuous recess, said flaps adapted to retain the sensitive surfaces within the frame, and an envelop surrounding 20 said frame and provided with a closed and an open end, said open end adapted to engage in said recess.
4. The combination of a photographic-plate holder, a door hinged thereto, a follower, and 25 a spring interposed between and connected to 30

said follower and door, said holder adapted to receive a sensitive-surface carrier retained in position by said door and spring-pressed follower.

5. In combination, a plate-holder 16, a door 35 17, a spring-pressed follower 18, and a sensitive-surface carrier 10 having enlargements at one end engaging in a recess formed in said holder, substantially as set forth.

6. In combination, a photographic - plate 40 holder provided with a light-excluding surface on its inner face surrounding the exposure-opening and with a recess, and a follower arranged in the holder and provided with a light-excluding surface and with a recess. 45

7. In combination, a photographic - plate holder provided with a light-excluding surface on its inner face surrounding the exposure-opening and with recesses, one of which 50 is adapted to receive the enlarged head of a sensitive-surface carrier, and a follower arranged in the holder and provided with a light-excluding surface and with a recess.

JAMES ASHFORD.

HERBERT EDWARD NEWEY.
